FEEDING DEVICE FOR INK FOUNTAINS

Hans Jovishoff and Ben W. Karp,
New York, N. Y.

Application March 5, 1952, Serial No. 274,864

5 Claims. (Cl. 101—364)

1

This invention relates to ink fountains of the type employed in printing presses. As is well known in this art, it is desirable to cause the ink in the fountain to constantly flow toward the fountain roller and various attempts have been made to secure the required result by means of different types of agitators. Such agitators, which generally assume the form of blades moved back and forth through the fountain, require mechanism to produce the required agitating movement; require cleaning, and are expensive to manufacture, install and maintain.

It is therefore an object of the present invention to provide an ink-feeding means for fountains in which the employment of agitators and other movable elements requiring expensive operating mechanism is dispensed with, and a simple, vertically disposed blade, extending for the interior length of the fountain is employed, and which is under required spring pressure to constantly urge the blade toward the periphery of the inking roller while the lower edge of the blade follows the inclination of the lower inner surface of the fountain, consisting of a fountain blade.

It is an object of the invention to provide a device of this character which can be very readily installed on various known types of printing presses; which can be readily adjusted, dismantled and cleaned and which will be capable of long continued use without requiring special care or maintenance.

With these and other objects to be hereinafter set forth, we have devised the particular arrangement of parts to be described and more particularly pointed out in the claims appended hereto.

In the accompanying drawing, wherein an illustrative embodiment of the invention is shown, Fig. 1 is a vertical sectional view through an ink fountain, showing the improved feed mechanism applied thereto;

Fig. 2 is a side elevation of one of the supporting brackets, and associated parts, looking at the same from the outer side;

Fig. 3 is a sectional view, taken on the line 3—3 of Fig. 1, looking in the direction of the arrows;

Fig. 4 is a sectional view, taken on the line 4—4 of Fig. 1, looking in the direction of the arrows;

Fig. 5 is a top plan view of the ink fountain and improved ink feeding device; and

Fig. 6 is a face view of the feeding blade.

Referring to the drawing, the ink fountain is generally indicated at 1, and the same includes the side walls 2 and 3 and the sloping bottom 4. Mounted on the sloping bottom 4 is the conventional adjustable distributor or fountain blade 5

by means of which the coating of ink applied to the inking roller 6 is regulated in the conventional manner. The elements thus far described, including the supporting members 7 for the ink fountain, are of well-known construction.

Fixedly secured on the top of each of the side members 2 and 3 of the ink fountain, are brackets 8 and 9, which are alike in construction so that a description of one will suffice. Each of the brackets 8 and 9 is provided with an inclined guide slot 10 arranged at an angle similar to the slope or slant of the bottom 4 and blade 5 thereon. Guided in each of the slots 10 is a guide block 11 that is provided at one end with an enlarged portion or head 12. The head is formed with a vertical passage 13 through which a pin 14 removably extends.

The ink-feeding blade is shown at 15, and it will be noted that the same constitutes a vertical partition that is constantly urged by spring pressure toward the inking roller to thereby force the ink 16 in the fountain toward and into contact with the periphery of the roller.

The lower end of the blade is beveled as indicated at 17, and the same rests against the distributor blade 5 and is held into contact therewith by the weight of the feed blade 15. The ink-feeding blade 15 is provided with a pair of lugs 18 through which the guide pins 14 extend, thus maintaining the blade vertically and also in proper alignment for the length of the ink fountain.

Located above the slot 10 in each of the brackets 8 and 9 is an undercut slot 19 which extends at an angle parallel to the lower slot 10. A spring 20, of the wishbone type, has one leg 21, secured by a wing-nut 24 on screw 22 in a block 23 which is adjustable in the slot 19. By tightening the wing-nut 24 on the screw 22, leg 21 of spring 20 may be fixedly held at any desired location in the slot 19 and thus the pressure of the spring regulated. The second leg 25 of the spring 20 is attached to the block 12 by means of a thumbscrew 26, carrying the wings 27. There is, of course, one of these springs at each end of the blade 15 and associated with each of the brackets 8 and 9.

From the foregoing, the operation of the improved ink-feeding device will be readily understood. When the fountain is to be filled the spring 20 may be retracted by loosening the screw 26 and bringing the leg 25 of the spring back to the rear end of the slot 10. When the fountain has been filled the spring may be set at the desired position to cause the same to urge the feed-

ing blade against the body of the ink in the fountain with the requisite pressure to constantly urge the ink toward and into contact with the periphery of the roller 6. Since the blade 15 is urged forwardly toward the roller 6, as well as downwardly and its bottom edge 15 is maintained in constant contact with the fountain blade 5, the ink 16 in the fountain will be urged forwardly under the pressure of the spring urged blade 15 and the roller 6 thus receiving the required coating despite a possible low level of ink in the fountain.

The device is such that it may be easily removed for cleaning or for other purposes, or readily disassembled when required. The insertion of the feeding blade 15 into the fountain, or its removal from the fountain, is very easily accomplished by removing the two pins 14.

Having described one embodiment of the invention, it is obvious that the same is not to be restricted thereto, but is broad enough to cover all structures coming within the scope of the annexed claims.

What is claimed is:

1. An apparatus of the character described, comprising an ink fountain having an inclined bottom member, an inking roller located at the outlet end of the fountain, a blade arranged vertically within the fountain and extending for the length of the fountain and movably supported by parts on the end walls of the fountain, said parts constituting supports for the opposite ends of the blade, each of said supports being provided with an inclined guide slot of an inclination similar to that of the inclined bottom member, the blades having elements riding in said slots, and springs for urging the blade toward the periphery of the roller and downwardly at an angle defined by the guide slots, said springs having ends engaging and adjustable in said supports.

2. An apparatus of the character described in claim 1, wherein the springs employed are wishbone springs, each of the said springs having one leg operative to urge the blade forwardly and downwardly and the second leg maintained in a fixed position, and means for locating and adjustably fixing the position of said second leg.

3. An apparatus of the character described comprising, an ink fountain, a roller at the outlet end of the fountain, brackets at the opposite ends of the fountain, each of said brackets being provided with a pair of inclined slots, a guide member located in one slot in each bracket, a blade disposed vertically within the ink fountain and extending for the length of the fountain, said blade being supported at each end by a guide member, a spring adjacent to each bracket, each

spring having a leg disposed in the second slot in each bracket, each spring having a second leg operatively engaging one of the guide members to thereby urge the blade toward the periphery of the roller while causing the lower edge of the blade to follow and be constantly located adjacent to the lower inside surface of the ink fountain.

4. An apparatus of the character described comprising, an ink fountain, a roller at the outlet end of the fountain, brackets at the opposite end walls of the fountain, each bracket having an upper and lower inclined slot, a guide member located in the lower slot in each bracket, a blade disposed vertically within the ink fountain and extending for the length of the fountain, the blade being engaged at each end by a guide member, a spring located adjacent to each bracket, each spring having a leg operatively engaging one of the guide members to thereby urge the blade toward the periphery of the roller while causing the lower edge of the blade to follow the lower inside surface of the ink fountain, and means for anchoring a second end of each spring in the upper slot, said spring-anchoring means being adjustable to or from the roller.

5. An apparatus of the character described comprising, an ink fountain having end walls, a roller at the outlet end of the fountain, a bracket mounted on the top of each of the end walls, each bracket being provided with a pair of parallel inclined slots, one of said slots in each bracket being located above the other, a guide member located in the lowermost slot in each bracket, a blade disposed vertically within the fountain and extending for the length of the fountain, said blade being supported at each end by one of the guide members, a spring adjacent to each bracket, said spring having an end disposed in the upper slot in the bracket, means in said slot for anchoring said end of the spring at selected locations in said upper slot, the spring having a second end operatively engaging one of the guide members to thereby urge the blade toward the periphery of the roller while causing the lower edge of the blade to follow and be constantly located adjacent to the lower inside surface of the ink fountain.
